JOHN W. W. HOLDEN, OF PROVIDENCE, RHODE ISLAND

THREADING DEVICE

Application filed March 4, 1931. Serial No. 519,965.

My invention relates to threading devices comprising a needle, a thread or cord engaged therewith and purposed for all uses to which such a needle and thread are employed, such for instance as sewing fabrics and threading, stringing or restringing beads or ornaments.

Heretofore in using a needle and thread the first step taken by the user was to "thread" the needle, by passing the thread end through the needle eye, forming, as the thread passed therethrough, a loop or fold. The thread end was drawn any desired substantial distance along the remainder of the thread, and the extremity of the threaded end knotted to an intermediate portion or to the end of the unthreaded portion. As a result the double thickness of the flexible member doubly distended any fabric through which it passed. In restringing beads or ornaments also the thread passages therethrough were clogged by the thread, particularly when the needle required to be passed through the passages a second time in an opposite direction. In both uses the presence of intermediate knots upon the flexible element made same unsatisfactory or impossible.

The essential objects of my invention are to overcome the above detailed disadvantages; to insure the passage of my device through an opening of minimum diameter; to insure that the flexible member be of no greater diameter at the needle eye than elsewhere throughout its length; to completely conceal the needle eye and insure a secure engagement of the eye with the cord; and to attain these ends in a structure capable of construction and assemblage by a quick, simple, and cheap process.

To the above ends primarily my invention consists in such parts, and in such combinations of parts as fall within the scope of the appended claims.

In the accompanying drawing which forms a part of this specification,

Figure 1 is a side elevation of a combined needle and cord embodying my invention,

Figure 2 is a side elevation of the needle in its original shape, and diagrammatically

showing in conjunction therewith the initial arrangement of the filaments, and

Figure 3, a fragmentary side elevation partly in vertical central section, of the finally interengaged needle and cord.

Like reference characters indicate like parts throughout the views.

In the drawing 10 represents a pliable needle formed from a single length of pliable metallic wire so bent as to form a substantially circular loop or eye 11 midway the wire, while the remainder of the wire is twisted or intertwined to form a spiral or volute shaft or body 12, all as shown in Figure 2. The pliable character of the shaft is often necessary in such uses as the restringing of beads or ornaments where abrupt changes in the direction of the needle and thread are necessary within a restricted space. The described form of needle is not exclusive, and its length may be, and usually is, proportionally greater than that illustrated. In sewing fabrics the point of the needle shaft is preferably less blunt, or more pointed, than herein shown.

The thread or cord 15 employed with the described needle is diametrically substantially circular, and throughout its length is composed of a plurality of textile strands or filaments 16 of cotton, silk, rayon, or the like, interengaged by braiding. By the same means the cord 15 is engaged with the needle 10.

A convenient method of forming the cord and attaching the cord and needle will now be described in conjunction with the showing in Figure 3, which is purely diagrammatic, throughout. Herein 19 represents the usual intersecting sinuous raceways in the top plate 21 of a braiding machine of usual construction with the braider bobbins moved by their carriers as commonly in the raceways. The needle 10 is firmly positioned vertically above the plate 21. Each of a plurality of filaments 16, preferably nine in number or multiples of nine, has one end extending from a filled bobbin, through the needle eye 11, to an opposite empty bobbin. The travel of the bobbins in their familiarly intersecting raceways twists the filaments into loops 27 snugly

engaging and concealing the eye 11, and continue to form longitudinally disposed laterally interengaging braids 28 constituting the completed cord.

- 5 During the described braiding movement of the strands there is a contemporaneous downward pull and twist thereof upon the pliable needle eye or loop 11 whereby the latter is downwardly elongated, as shown in
10 Figure 3, thereby diminishing the otherwise excessive diameter of the upper end of the cord, which is not desirable.

It will be observed that not only is the needle eye wholly concealed in the cord 15, but
15 that the diameter of the portion of the latter embracing the eye is no greater than elsewhere; also, that the braided interengagement of the filaments with the needle eye and with each other insure such a secure attachment
20 of the needle with the cord as to prevent severance under a maximum strain.

I claim:—

1. In a device of the character described, a metallic needle comprising a shaft and a terminal loop, and a cord comprising braids fixed at their ends to the loop, the cord being of greater cross section than the needle.
2. In a device of the character described, a needle comprising a shank and a loop, and a cord comprising a plurality of filaments interbraided with and embracing the loop.
3. In a device of the character described, a metallic needle comprising a shank and a terminal loop, and a cord comprising textile filaments braided to the loop and enclosing the same.
4. In a device of the character described, a metallic needle comprising a flexible shaft and a flexible loop, and a cord comprising interengaged braids terminating looped portions passing through the terminal loop and concealing the same.

In testimony whereof I have affixed my signature.

JOHN W. W. HOLDEN.
